ELECTRICAL CONDUCTOR

William T. Barrans, Towson, and Paul M. Cole,
Dundalk, Md., assignors to Western Electric
Company, Incorporated, New York, N. Y., a
corporation of New York

Application March 3, 1939, Serial No. 259,508

15 Claims. (Cl. 174—69)

This invention relates to an electrical conductor and more particularly to an electrical conductor of the retractile extensible type.

An object of the invention is to provide an effective and compact retractile cord.

In accordance with one embodiment of the invention three conductors are enclosed in a braided covering to form a coiled cord, the outer conductor being of greater length than the inner conductors and the tension in the strands forming the braid being so proportioned as to provide a natural twist in the conductor.

A complete understanding of the invention may be had by reference to the following description taken in conjunction with the accompanying drawings, in which—

Fig. 1 is a front elevation of a machine for making the conductor of this invention;

Fig. 2 is an enlarged fragmentary sectional plan view taken on the line 2—2 of Fig. 1;

Fig. 3 is a sectional view taken on line 3—3 of Fig. 2;

Fig. 4 is a sectional view showing a cross section of the cord taken on line 4—4 of Fig. 3;

Fig. 5 is a detail view of a cord embodying the invention; and

Fig. 6 is a cross-sectional view of another cord embodying the invention.

Referring now more in detail to the drawings, a braider is shown in Fig. 1 having a frame 6. The braider has a rotating braider head carrying a series of cops 7 of yarn rotating in a counterclockwise direction and a second series of cops 8 rotating in a clockwise direction looking at the machine from above.

The details of the mechanism of this machine are more fully disclosed in the patent to Miller, 1,602,442 of October 12, 1926, and will not be described herein.

A plurality of conductors 9, to be covered with braiding, pass upwardly through the braider head. The upper portion 11 of the braider head is stationary and has a cross piece 12 provided with a Y-shaped fork 13 and a cut out portion 14 forming triangularly spaced guides for the three conductors. Attached to the cross piece is also a guide 15, the guiding portion of which is U-shaped. From the position shown in Figure 2 the conductors and braided covering rotate 90° in a clockwise direction before reaching the capstan 19 and the upper portion of the guide 15 is twisted so as to substantially follow the twist in one of the conductors. The twist thus placed in the cord assists in the helical coiling of the cord. As the yarn 16 is interbraided on the conductors it contacts with two of the conductors but is prevented from contacting the third conductor by the guide 15 until it is close to an axial delivery take-up capstan 19. In passing over the capstan the two inner conductors lie

substantially against the outer periphery of the capstan and the third conductor lies radially outward therefrom. Due to this arrangement it will be seen that the outer conductor forms a convolution of greater diameter than the inner conductors and should be longer than the inner conductors. The outer conductor, therefore, slips through the guide 15 and moves at a greater speed than the inner conductors. This is possible due to the guide 15 which spaces the braid from the outer conductor and permits it to move within the braid. Since the outer of the three conductors is of a greater length than the inner conductors it therefore has a natural tendency to form a helical coil.

This natural tendency of the cord to form a helical coil may be further increased by applying different tensions to the braided yarn. For instance, in making a helical cord having a right hand pitch the tension on the yarn from the series of cops 7, which travel in a counterclockwise direction looking downwardly at the cops in Figure 1, may be four ounces on each thread, while the tension on the yarn from the cops 8, which travel in a clockwise direction, may be eight ounces per thread.

A cord made in this manner with the outer conductor of greater length than the inner conductors and the tension on the strands of the braiding greater in one direction than in the other, will form a helical extensible retractile coil without any other elastic materials. In some cases, however, it may be desirable to have elastic materials either as a part of the braided covering or in addition thereto. When using elastic materials as a part of the braided covering, rubber strands or preferably thread covered rubber strands of a type well known in the art may be used on the cops 8 which travel in a clockwise direction and have the higher tension applied thereto when making a retractile coil of right hand pitch. If it is desired to make a coil of left hand pitch the relative tensions in the threads are reversed.

Fig. 6 illustrates a cord in which the threads drawn from the cops 8 are of an elastic material such as rubber.

If it is desired to incorporate elastic material in the coil in addition to the braid, elastic strands 17 are passed between tension rolls 18 which are driven at a predetermined speed in relation to the capstan 19 to apply a tension of approximately 180% to the rubber strands. These rubber strands are fed upwardly between the arms 55 of the fork 13 of the cross piece 12 as shown in Figure 2.

It may be desirable in some cases to use an elastic member 21 which passes through the convolutions of the retractile coil and is attached to the ends of the cord by the tips 22. This

construction is particularly useful when the cord embodies no other elastic materials and relies for its elasticity on the construction which takes advantage of the inherent elasticity of the conductors and braiding material.

While particular tensions on the yarn and other specific embodiments have been herein disclosed it will be evident that many changes and modifications may be made therein without departing from the spirit and scope of the invention.

What is claimed is:

1. A retractile electric cord comprising a plurality of helically coiled conductors, one of the conductors forming convolutions of greater diameter than another conductor, said conductors being substantially unstressed in the retracted state of the cord, and a fabric jacket covering said conductors.

2. A retractile electric cord comprising a plurality of helically coiled conductors, one of the conductors having a longer length per convolution than another, said conductors being substantially unstressed in the retracted state of the cord, and a braided covering over said conductors.

3. A retractile electric cord comprising a plurality of helically coiled conductors, one of the conductors forming convolutions of greater peripheral length than another conductor said conductors being substantially unstressed in the retracted state of the cord, a covering of interbraided strands passing in opposite spirals around said conductors, the tension in the strands going in one direction being greater than the tension in the strands going in the other direction.

4. A retractile electric cord comprising three conductors formed into a helix, said conductors forming a triangle in cross-section with two of the conductors being of equal length, and the third conductor being of a greater length, said conductors being substantially unstressed in the retracted state of the cord, and a fabric covering said conductors.

5. A retractile electric cord comprising three conductors formed into a helix, said conductors forming a triangle in cross-section with two of the conductors forming convolutions of equal peripheral length and the third forming a convolution of greater length, said conductors being substantially unstressed in the retracted state of the cord, a covering of interbraided strands over said conductors in which the strands pass spirally in opposite directions around the conductors, the strands going in one direction being under greater tension than the strands going in the opposite direction.

6. An electric cord comprising a helically coiled conductor having a covering of interbraided strands passing in opposite spirals around the conductor, the strands passing around the conductor in one direction being elastic and the strands passing around the conductor in the opposite direction being relatively inelastic.

7. An electric cord comprising a helically coiled conductor having a covering of strands passing in opposite spirals around the conductor, the strands passing around the conductor in one direction being elastic and the strands passing

around the conductor in the opposite direction being relatively inelastic.

8. A retractile electric cord comprising a plurality of helically coiled conductors, one of said conductors forming convolutions of a greater peripheral length than another, said conductors being substantially unstressed in the retracted state of the cord, and a covering for said conductors of interbraided strands passing in opposite spirals around the conductors, the strands passing in one direction being elastic and the strands passing around the conductors in the opposite direction being relatively inelastic.

9. A retractile electric cord comprising a plurality of helically coiled conductors, one of said conductors being of greater length than another conductor, said conductors being substantially unstressed in the retracted state of the cord, a braided covering over said conductors, and elastic means tending to retain said cord in helically coiled form.

10. An electric cord comprising a plurality of helically coiled conductors, one of said conductors being of greater length than another, and an elastic element attached to the ends of the cord and passing through the convolutions thereof in an axial direction.

11. A retractile electric cord comprising a plurality of conductors in helically coiled form, one of said conductors being of greater length than another conductor, said conductors being substantially unstressed in the retracted state of the cord, a covering of braided strands having strands passing in opposite spirals around the cord, the tension in the spirals going in one direction being greater than the tension in the strands going in the opposite direction, and an elastic element attached to the ends of the cord and passing through the convolutions in an axial direction.

12. An electric cord comprising a helically coiled conductor having a covering of interbraided strands passing in opposite spirals around the conductor, at least one of the strands passing around the conductor in one direction being elastic to cause the cord to coil helically when unstressed, the strands passing around the conductor in the opposite direction being relatively inelastic.

13. An electric cord comprising a helically coiled conductor having a textile covering, and an elastic element having an elasticity comparable to that of rubber spirally disposed around said conductor so fixed relative to the conductor as to impart a torsional force which causes the cord to coil helically when unstressed.

14. An electric cord comprising a helically coiled conductor having a covering of braided strands and a stretched rubber strand spirally disposed around said conductor to cause the cord to coil helically when unstressed.

15. An electric cord comprising a helically coiled conductor having a covering of interbraided strands and an elastic element interbraided in said covering and spirally disposed around said conductor to cause the cord to coil helically when unstressed.
